UNITED STATES PATENT OFFICE.

HARRY M. THOMPSON, OF WASHINGTON, PENNSYLVANIA.

MUFFLE-LEER.

1,257,150.

Specification of Letters Patent. Patented Feb. 19, 1918.

Application filed October 1, 1917. Serial No. 194,132.

To all whom it may concern:

Be it known that I, HARRY M. THOMPSON, a citizen of the United States of America, and resident of Washington, county of Washington, and State of Pennsylvania, have invented certain new and useful Improvements in Muffle-Leers, of which the following is a specification.

This invention relates broadly to annealing furnaces or leers for glassware, and more particularly to a leer of the continuous muffle type.

Much trouble, inconvenience and expense has been experienced in the use of muffle leers, as heretofore constructed, due to the instability of the flues or courses through which are conducted the gases and products of combustion employed in heating the leer chamber, said flues being commonly composed of hollow tiles disposed in arch form over the leer chamber. Due to the intense heat to which they are subjected, the tiles composing such flues become warped, distorted and otherwise injured to the extent that cracks, fissures and the like quickly develop, permitting gas and products of combustion to escape into the leer chamber where, coming into contact with the ware, it discolors and otherwise contaminates the ware rendering the same practically valueless. This is especially true in cases in which raw producer gas is the fuel employed. It has heretofore been necessary, when such leakage occurred, to shut down and cool the leer, and then to tear out and rebuild or otherwise repair the defective flue or flues.

It is the primary object of the present invention to provide a muffle-leer which will, in large measure, obviate the objectionable features of former leers of this character, above referred to, such leer being so constructed that the danger of leakage of undesirable impurities from the muffle chamber to the leer chamber is minimized, affording comparative freedom from risk of contaminating the ware.

A further object of the invention is to provide a muffle-leer in which the muffle chamber, or the chamber through which the products of combustion are directed, is separated from the leer chamber by a division wall or floor having substantial supports and which is not readily liable to become so affected by heat as to permit leakage, and which, when leakage does occur, may be re-

paired promptly, or without the delays incident to the repair of the former leer structures referred to.

Another object is to provide a leer which is adapted to the use of natural gas, producer gas, oil, or any other fuel.

With these and other objects in view, the invention resides in the features of construction, arrangement of parts and combinations of elements which will hereinafter be described, reference being had to the accompanying drawings, in which—

Figure 1 is a central longitudinal section of a muffle-leer embodying my invention;

Fig. 2 is a vertical section of the same on line 2—2, Fig. 1; and—

Fig. 3 is a horizontal section on line 3—3, Fig. 1.

Referring to said drawings, in which like designating characters distinguish like parts throughout the several views—

1 indicates the front end-wall and 2 and 3 the side walls of a furnace or leer of the muffle type, and 4 designates the leer chamber which is to be heated, said chamber having an endless ware carrier, as 5, operating therein. Located directly beneath the usual arch 6, which is formed of fire brick or other refractory material, is a muffle chamber, generally designated by the numeral 7, through which the burning gases and heated products of combustion are conducted to the flue 8 which leads to the stack. Said muffle chamber 7 comprises a chamber 7^a of suitable capacity located adjacent to the front end of the furnace or leer, and a plurality of relatively smaller chambers 7^b arranged in succession and separated by division walls or baffles 9 having openings or ports 7^c therethrough located in staggered relation whereby is constituted a tortuous passage for the heated products of combustion. As is obvious, it is designed that the passage of the products of combustion to the stack flue through said chambers and ports shall be so retarded that much of the heat carried thereby shall be imparted to the underlying leer chamber 4.

Said leer chamber is separated from said muffle chamber by a floor-like division wall 105 which is of a substantially horizontal form. In the construction of said division wall or floor I employ a plurality of transversely disposed metal beams or girders 10, preferably of inverted-T shape, suitably spaced 110

apart and supported by hanger rods 11. The heads of said beams 10 serve as supports upon which rest the opposite lateral edges of interengaged plates 12 of refractory tile which are adapted to absorb heat from the products of combustion passing thereover and to impart said heat to the leer chamber 4. Resting upon said tiles 12 close to the opposite faces of the upright web portions of the supporting beams 10 and overlying said web portions are fire brick walls 13 upon which rest the division walls or baffles 9.

The hanger rods 11 are directed vertically through the arch 6, baffles 9 and beams 10 and serve to suspend the said floor of the muffle chamber and the superposed baffles from beams 14 or the like located over the furnace. Said rods are preferably formed with cross-heads 11* at their lower ends, and when they have been directed downward through alined rectangular openings 15, 16 and 17 provided for said cross-heads in the arch 6, baffles 9 and beams 10, respectively, they are given a quarter turn to cause said heads to assume underlying supporting relation to said beams, transverse countersinks for the reception of said heads being preferably provided in said beams as indicated in dotted lines in Fig. 1.

When the fuel employed is natural gas, clean producer gas or oil, the same is preferably directed from suitable nozzles or burners, as 19, through openings 20 in the front wall to the chamber 7* of the muffle 7 which, in such case, constitutes a combustion chamber. On the other hand, when raw producer gas, coal or other fuel is used, it is preferable that the gases and products of combustion enter said chamber 7* through ports 21 in the side walls 2 and 3, suitable flues, as 22, leading through said side walls from a suitable furnace, as 23, in which combustion initially occurs.

It will be obvious that the herein described floor or division wall which separates the muffle and leer chambers will not readily become distorted so as to permit leakage of gases into the leer chamber, the tiles being positively supported in a much more substantial manner than is possible where a plurality of flues composed of interengaging hollow tiles disposed in arches, as ordinarily, is employed. Further, it is apparent that said floor may be readily repaired when leakage does occur, it being only necessary to replace the injured tile or other part without tearing out and rebuilding any considerable part of the structure.

What is claimed is—

1. A muffle leer comprising a leer chamber and a superposed muffle chamber, a substantially horizontal division wall separating said chambers, said wall consisting of a plurality of spaced parallel metal beams and plate-like tiles interposed between and supported by adjacent beams, and a plurality of baffle walls resting directly upon said beams and providing a tortuous passage through said muffle chamber for the products of combustion. 60

2. A muffle leer comprising a leer chamber and a superposed muffle chamber, a substantially horizontal division wall separating said chambers, said wall consisting of a plurality of spaced parallel metal beams and plate-like tiles interposed between adjacent beams and having their lateral edges supported by said beams, means suspending said beams, and baffle walls dividing said 65 muffle chamber into a plurality of communicating chambers, said baffle walls being mounted upon said beams. 75

3. A muffle leer comprising a leer chamber and a superposed muffle chamber, a substantially horizontal division wall separating said chambers, said wall consisting of a plurality of spaced parallel metal beams of inverted-T shape and plates of refractory material interposed between said beams and having their lateral edges resting upon the laterally disposed wings of adjacent beams, and baffle walls dividing said muffle chamber into a plurality of communicating compartments, said baffle walls being mounted upon 95 said beams. 90

4. A muffle leer comprising a leer chamber and a superposed muffle chamber, a substantially horizontal division wall separating said chambers, said wall consisting of a plurality of spaced parallel metal beams of inverted-T shape and plates of refractory material interposed between said beams and having their lateral edges resting upon the laterally disposed wings of adjacent beams, hanger rods suspending said beams, and a plurality of baffle walls disposed within said muffle chamber and mounted upon said beams, said walls having ports therethrough disposed in staggered relation whereby is 100 formed a tortuous path for the products of combustion. 105

In testimony whereof, I affix my signature in presence of a subscribing witness.

HARRY M. THOMPSON.

Witness:

W. F. KEEFER.
